UNITED STATES PATENT OFFICE.

ARTHUR J. WIDMER, OF WEBSTER GROVES, MISSOURI, ASSIGNOR, BY MESNE ASSIGNMENTS, TO WIDMER ENGINEERING COMPANY, OF ST. LOUIS, MISSOURI, A CORPORATION OF MISSOURI.

CLIP FOR HOLDING PLASTER-BOARDS.

1,277,514.

Specification of Letters Patent.

Patented Sept. 3, 1918.

Application filed May 28, 1916. Serial No. 99,959.

To all whom it may concern:

Be it known that I, ARTHUR J. WIDMER, a citizen of the United States, and a resident of Webster Groves, in the county of St. Louis and State of Missouri, have invented a new and useful Improvement in Clips for Holding Plaster-Boards, of which the following is a specification.

This invention relates to plaster walls and ceilings wherein thin boards made of gypsum, pulp, fiber, and the like, are used for supporting the plaster, and the invention consists in an improved clip for supporting the plaster boards to the wall studding or ceiling supports.

The object of the invention is an inexpensive clip which can readily be attached to the support and which holds the plaster boards securely in proper alignment. Further objects of the invention appear in connection with the following description of the various devices shown in the drawings, and what the invention consists in is more particularly defined in the appended claims.

In the drawings, wherein the same reference characters designate the same or similar parts in the several views;

Figure 1 is a cross-section through a ceiling parallel to a support, showing an end view of one form of clip;

Fig. 2 is a cross-section of the same ceiling at right angles to a support, showing a side view of the clip;

Fig. 3 is a perspective view of the clip shown in Figs. 1 and 2;

Fig. 4 is a cross-section of a wall at right angles to the studding, showing a modified form of clip;

Fig. 5 is a perspective view of the form of clip shown in Fig. 4; and

Fig. 6 is a perspective view of a piece of metal studding having integral back supports against which the plaster boards are held by integral tongues and plates carried thereby.

In the construction shown in Figs. 1, 2 and 3, the supports 10 for the ceiling are metal channels with spaced slots 11 in their lower edges for clips 12. Each clip 12 comprises an inverted channel-shape middle portion and two parallel spacers 13 projecting from one edge and a flanged spacer 14 projecting from its opposite edge in a plane parallel to the spacers 13, the lower face of the spacer 14 being in the same plane as

the spacers 13, and a tongue 15 which projects from the middle of the clip between and at right angles to the spacers 13. The clips 12 are arranged in the slots in the lower flanges of the supports 10 with their tongues 15 projecting down, and with the parallel spacers 13 below the supports, the flanged spacers 14 resting on the lower flanges of the supports with the extremities of their flanges projecting down over the edges of the lower flanges of the supports and terminating below them in the plane of the spacers 13. The edges of the plaster boards 16 rest on the ends of plates 17 which are supported by the tongues 15. The plates have slots 70 through their middles, and the ends of the tongues pass through the slots in the plates and are bent over. The plates 17 hold the edges of the plaster boards up against the parallel spacers 13 and lower faces of the flanged spacers 14, to locate them in proper horizontal alignment.

The clip shown in Figs. 1, 2 and 3 may be used also in walls by making slots in both flanges of the studs, as shown in Fig. 4. The clips 18 shown in Fig. 4 are arranged on the outer faces of the flanges 19 of the channel-shape support 20, and are secured by hook prongs 21 which are bent up from the clips and hooked through slots 22 in the web of the support. The plaster boards 16 are either penetrated by the tongues 23 of the clips, or their edges are held against the clips by slotted plates 24 which are secured by the tongues.

The clips shown in Fig. 4 may be secured to the supports at the place of manufacture and shipped already assembled. The clips may also be made integral with the support instead of being separately formed and secured thereto. Fig. 6 shows a channel-shape support 25 having integral clips, the spacing portions 26 being punched out of the web and the tongues 27 being punched out of the flanges 28. The tongues 27 are twisted parallel to the web and lie nearly in the plane of the web, so the flanges 28 serve as spacers for the plaster boards on the side of the tongues opposite the spacing portions 26.

It is evident that modifications in the shape and dimensions of the spacers, tongues and plates may be made without departing from the invention, and the invention is not restricted to the forms shown in the drawings.

I claim the following as my invention:

1. The combination with plaster boards of a support therefor having spacing members thereon, said spacing members having laterally extending portions constituting abutments for the plaster boards and a perpendicularly extending tongue adapted to project beyond the face of the plaster boards, and a plate carried by said tongue 10 and holding said plaster boards against said spacing members.
2. The combination with plaster boards of a support therefor having spacing members thereon, said spacing members having laterally extending portions constituting abutments for the end portions of adjacent plaster boards and a perpendicularly extending tongue adapted to project through the space between adjacent plaster boards, and 20 a perforated plate impaled on said tongue and overlapping the ends of said boards, said tongue being bent to hold said plate in place.
3. In combination with a support for plaster boards, said support having slots in it at spaced intervals, clips arranged in said slots, said clips comprising spacing members arranged to bear against the edges of the plaster boards on each side of said support and having tongues projecting between the edges of the plaster boards, and plates carried by the tongues and supporting the edges of the plaster boards against the spacing members.
4. In combination with a support for plaster boards, said support having slots in it at spaced intervals, clips arranged in said slots, said clips comprising members arranged over the support and having tongues projecting beyond the face of the plaster 40 boards, and plates carried by the tongues and supporting the plaster boards.
5. In combination with a support for plaster boards, said support having spaced slots therein, clips arranged in said slots, 45 said clips comprising middle portions engaging the support, spacers on each side thereof bearing against the plaster boards, and tongues projecting beyond the face of the plaster boards, and plates carried by the 50 tongues and supporting the plaster boards against the spacers.

Signed at St. Louis, Missouri, this 24th day of May, 1916.

ARTHUR J. WIDMER.
